UNITED STATES PATENT OFFICE.

FRANCIS W. GIBSON, OF BOSTON, MASSACHUSETTS, ASSIGNOR TO H. D. BEACH COMPANY, OF BOSTON, MASSACHUSETTS, A CORPORATION OF OHIO.

DISPLAY-RACK.

1,294,258.

Specification of Letters Patent. Patented Feb. 11, 1919.

Application filed October 7, 1915. Serial No. 54,669.

To all whom it may concern:

Be it known that I, FRANCIS W. GIBSON, a citizen of the United States, residing at Boston, county of Suffolk, Commonwealth 5 of Massachusetts, have invented certain new and Useful Improvements in Display-Racks, of which the following is a specification.

This invention relates to display racks and particularly to a rack for exhibiting 10 rows of canistered goods as, for example, boxes of crackers, cakes or the like.

In devices of this character, it is highly desirable that the canisters shall be displayed with their hinged covers disposed 15 in freely accessible relation so that access may be had to the contents of the canisters without removing the canisters from the supporting shelves of the rack and without liability of upsetting the containers or spilling 20 the contents thereof. It is also desirable that the display itself shall be pleasing in appearance and that the rack shall be constructed with a view of providing matter descriptive thereof, with the minimum 25 amount of available floor space.

To the end therefore of providing a display rack in which the above indicated features will be present, I have devised my present invention.

30 The construction and manner of using a display rack of this invention will be more fully described in the specification which follows. In the drawings accompanying that specification, I have shown as an illustrative embodiment a form of display rack which not only clearly discloses the principles of my invention, but is in itself a rack which has proved satisfactory in use and well adapted to the requirements of 35 manufacture. Throughout specification and drawings, like reference numerals are correspondingly applied, and in the drawings:

Figure 1 is a front elevation of a display rack embodying my invention, and

Fig. 2 is a vertical section therethrough.

The display rack of the present invention consists of a pair of spaced side members 1, which may be formed of any desirable material, and are preferably formed of some 50 sheet material, the edges of which are turned as indicated at 2 in order to afford a more finished appearance as well as to provide the requisite stiffness. The case is braced on the back by a right angled strip 3 extending transversely across the rack between the

members 1 at the lower ends thereof. The member 3 may be used as a support for articles in addition to its bracing function. Additional rigidity for the side members may be provided by any suitable braces as 60 the diagonal strips 4 which brace the structure at the back.

The side members 1 of the rack are connected by a plurality of transversely disposed vertically spaced supporting elements. 65 The supporting elements may be of any desired form, and are preferably simple shelves arranged in superimposed upwardly and outwardly obliquely extended relation as best shown in Fig. 2. Each shelf element 70 consists of a support 5 for the bottom wall of a row of hinged cover containers 6, an upwardly and rearwardly extended wall 7 adapted to back the rear wall of the containers and a downwardly extended front 75 wall 8 disposed to mask the container row next beneath. The edges of the walls 5, 7 and 8, may be turned as indicated to avoid sharp edges and to improve the appearance of the rack. The walls 8 and the side members 1 of the rack may bear any suitable advertising matter. The wall 8 of the lowermost shelf is not turned but instead is extended downwardly to the bottom of the rack and secured to the side members, as 80 shown.

The containers 6 are therefore supported in spaced superimposed rows on the shelf elements. Each container row is arranged in upwardly inclined relation, as to position 90 its hinged cover 9 in freely accessible position facing the front open side of the rack.

Arranged at a suitable distance above each shelf element and extending transversely between the side members 1 of the rack in parallelism to the shelf elements is a plurality of sleeved guide and bearing rods 10. The rods 10 lie between two parallel planes, one of which passes through the front edge of the next lower shelf and the other of which 100 passes through the upturned flange 7 of said shelf. Each rod is disposed sufficiently above the next lower shelf to allow the containers to be freely inserted and removed, but close enough to define the position of 105 the containers and to prevent tipping thereof. In practice the tie rods are found to function most satisfactorily when located slightly in rear of the plane which passes vertically of the rack through the shelf 110

at its juncture with the flange 7. So located, the tie rods overlie the top surface of the container at its overhang or displacement relative to the shelf. The sleeves for said rods are indicated at 11. These sleeves define, with the shelf elements, opened end spaces or compartments into which the rows of containers are insertable by simple sliding movement. The sleeves 11 bear against 10 the top walls of the containers and in addition to their function of guiding the containers into the shelf spaces in the upwardly inclined position, shown in the drawings, serve by reason of the overhead bearing thus 15 provided to maintain the containers in such position while permitting their hinged covers 9 to be exposed in freely accessible position relative to the open side of the rack. The rods 10 are provided at their outer ends 20 beyond the side walls 1 of the rack with ornamental nuts 12, which are adapted to be set up thereon against said side members.

In using the display rack of the present invention, the rows of containers are slid 25 into the spaces defined by the shelf elements and the sleeves 11, with their hinged covers 9 exposed beyond the front open face of the rack. In positioning the containers in this relation, the sleeves act to guide the 30 containers into the shelf spaces. Where access to the contents of a container is desired, it is simply necessary to swing the hinged cover 9 thereof downwardly and outwardly as indicated by the dotted line showing of 35 Fig. 2. The container is prevented from sliding from the shelf or from tipping upwardly sufficiently to spill its contents by the overhead bearing maintained on the top face of the container by the sleeves 11. 40 When it is desired to remove a container in its entirety, as for the purpose of refilling or the like, the container is simply slid entirely out of the space defined by a sleeve 11 and the shelf member immediately there- 45 beneath. This sliding movement is an upwardly directed movement until the rear wall of the container is carried past the rod 11, whereupon the container is drawn out by direct horizontal sliding movement. 50 My rack therefore affords not only a complete and effective display and support for packaged goods of this character, but permits the containers to be disposed with their hinged covers accessibly arranged with relation to the front opening of the rack, so that 55 access to the contents of the containers may be had without any movement whatever of the containers outwardly, and wherein liability of the containers tilting to slide off

from the shelves or spilling their contents 60 is positively prevented by the overhead bearing of the member 11.

Various modifications in the construction and arrangement of the parts of the rack may obviously be made without departing 65 from the spirit of my invention if within the limits of the appended claims.

What I therefore claim and desire to secure by Letters Patent is:

1. A display rack, consisting of spaced side 70 members, a series of superposed rearwardly sloping shelves arranged between and rigidly connecting said side members and having upturned rear flanges substantially at right angles thereto, each shelf adapted to support a row of covered containers in upwardly and outwardly inclined relation and with 75 their covers foremost, and tie rods connecting said side members and disposed transversely of the rack and lying between two 80 parallel planes, one of which passes through the front edge of the shelf next below and the other of which passes through the upturned rear flange of said shelf, and said rods disposed in guiding and confining relation to 85 the containers whereby to define the position of the containers and to prevent tipping of a container when its cover is displaced to permit access to the contents thereof.

2. A display rack comprising spaced side 90 members, a vertical series of superposed hod-shaped shelves arranged between and rigidly connecting said side members and adapted to support respective rows of hinged-covered containers with their hinge-covers foremost, tie rods disposed above said shelves and connected to said side members and defining with said shelves an open ended receiving space for the containers, and sleeves 95 fitted over said tie rods and adapted to bear 100 on the rear, top portions of the containers to prevent tilting thereof.

3. A stock displaying and canister supporting device, comprising a series of superposed hod-shaped shelves, arranged horizontally and rigidly connected, for supporting respective rows of canisters with their hinged covers foremost, and guiding and supporting devices disposed relatively to the shelves for defining the position of and preventing the tipping of the canisters, and adapted to bear upon the tops thereof.

In testimony whereof I affix my signature in presence of two witnesses.

FRANCIS W. GIBSON.
